UNITED STATES PATENT OFFICE.

DAWSON M. TAGGART, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,355,926.

Specification of Letters Patent. Patented Oct. 19, 1920.

Application filed October 23, 1918. Serial No. 259,367.

To all whom it may concern:

Be it known that I, DAWSON M. TAGGART, a citizen of the United States, residing at East Orange, in the county of Essex, State 5 of New Jersey, have invented certain new and useful Improvements in Telephone-Exchange Systems, of which the following is a full, clear, concise, and exact description.

This invention relates to telephone exchange systems and more particularly to those in which trunk circuits are employed in completing connections between telephone lines terminating at telephone switchboards or offices.

15 In such systems it is desirable to provide signaling means whereby the operators handling the connections are definitely advised as to the status of the called telephone station. Especially in systems employing 20 operator controlled means for signaling the desired station it is very desirable that the completing or trunk operator should receive an accurate indication that such station has answered.

25 It is the object of the present invention to provide an improved signaling system of this character which is simple and inexpensive and which provides a signaling means which, although unaffected by the 30 changes in the electrical characteristics of the trunk circuit and the connected line circuit, incident to the establishment of the telephonic connection, will furnish an accurate signal upon the response of the called 35 station.

To attain this object in accordance with the feature of the invention, the locking of the usual ringing signal control relay of a trunk circuit for indicating the response of 40 the called station, is controlled by means, associated with the signaling device, for preventing a premature indication being given, due to incidental momentary operations of the controlling supervisory relay 45 prior to the answer of the called station.

The nature of this invention will fully appear from the following specification and the annexed drawing in which the figure shows diagrammatically a trunk circuit embodying the invention, together with sufficient portions of line and link circuits for coöperation therewith, to properly illustrate the operation of such a system.

In the accompanying drawing, a trunk 55 circuit B interconnects the switchboards or

offices X and Y, terminating at office Y in a plug 1 and at office X in a jack 2. An ordinary line circuit equipped with the usual line relay 3, cut-off relay 20 and line signal 4, and terminating in a jack 5, connects an ordinary subscriber's station C with office Y. A connecting or link circuit A, of any usual type, is provided at office X and terminates in plug 6 for connection with the jack 2 of the trunk circuit B. All portions of the link circuit A, not essential to the proper understanding of the invention, have been omitted. The trunk circuit B is equipped with a ringing key 7, a supervisory relay 8, a trunk relay 9 and a signal 60 control relay 10, which relays coöperate to control a ringing and guard signaling lamp 11 and a disconnect signaling lamp 19. Associated with the signaling lamp 11, and connected in parallel therewith, is a slow 65 release relay 12 controlling the locking circuit of the signal control relay 10.

It is thought that the invention may be more fully comprehended from the following description of the operation of the system shown.

Assuming that the operator at switchboard X desires to call station C on the line circuit terminating in jack 5, at the switchboard Y, the operator at switchboard Y is 85 notified in some suitable manner over a call circuit or otherwise and assigns the trunk circuit B. The operator at switchboard X thereupon inserts plug 6 of the link circuit A into the jack 2 of the trunk circuit B. 90 The lamp 13 is lighted over a circuit extending from battery through the lamp 13, the resistance 14, and the sleeve contacts of plug 6 and jack 2, to ground. Relay 9 is also operated over a circuit extending from 95 battery through the winding of relay 15, the ring contacts of plug 6 and jack 2, the windings of relay 9 in series, the tip contacts of jack 2 and plug 6, to ground. However, due to the high resistance of the windings of 100 relay 9 in series the supervisory relay 15 of the link circuit A is not operated at this time. The operation of relay 9 causes the lighting of lamp 11 over a circuit extending from battery through the lamp 11, the 105 normal contact of relay 10 and the alternate contact of relay 9, to ground. Relay 12 is also operated over a circuit extending from battery through the winding of relay 12, the normal contact of relay 10 and the alter- 110

nate contact of relay 9, to ground. The operator at switchboard Y after making the usual busy test and finding that the line leading to station C is idle, thereupon inserts plug 1 into jack 5, operating relays 20 and 16, over a circuit extending from battery through the winding of relay 16, the sleeve contacts of plug 1 and jack 5 and the winding of relay 20, to ground. The operation of relay 20 thereupon removes the line relay 3 and its associated line signal 4 from their normal association with the line circuit leading to station C. The relay 16, in closing its upper contact, establishes the continuity of the tip conductor of the trunk circuit.

The operator at switchboard Y actuates the ringing key 7 which, in the usual manner, impresses signaling current upon the conductors of the line circuit associated with the station C to cause the operation of the usual signaling device at the called station. The ringing key 7, being released, after the signal at the called station has been operated, the trunk circuit apparatus is in condition to respond to the answer of the called station. Upon the response of such station the supervisory relay 8 is operated over a circuit extending from battery through the winding of relay 8, the lower normal contact of ringing key 7, the ring contacts of plug 1 and jack 5, through the apparatus at the called station, the tip contacts of jack 5 and plug 1 and the upper alternate contact of relay 16, to ground. The operation of the relay 8 places the left-hand winding of relay 10 in parallel with the left-hand high resistance winding of relay 9, thereby causing the operation of relay 15 due to the consequent decrease of the resistance of the associated circuit. The operation of relay 15 extinguishes lamp 13 in the usual manner by the establishment of a shunt circuit therearound including the resistance 21. The extinguishment of the lamp 13 notifies the operator at switchboard X that the called station has answered. Relay 10 also operates due to the current flowing through its left-hand winding and in opening its normal contact opens the circuits of lamp 11 and of relay 12. However, the locking circuit of relay 10 is not completed until slow release relay 12 has fully released. Upon the complete release of relay 12, the relay 10 is locked over a circuit extending from battery through the lower contact of relay 16, the right-hand winding of relay 10, the normal contact of relay 12, the alternate contact of relay 10 and the alternate contact of relay 9, to ground. The operator at switchboard X may now converse with the station C through the operation of the usual listening key 17. Upon the completion of the conversation between the calling subscriber and the subscriber at station C the

operator at switchboard X removes the plug 6 from the jack 2, thereby restoring the apparatus associated with the link circuit A to its normal condition and releasing relay 9 to cause the lighting of the disconnect lamp 19 over a circuit established from battery through the lower contact of relay 16, the lamp 19 and the normal contact of relay 9, to ground. Upon observing the lighted condition of lamp 19, the operator at the switchboard Y removes the plug 1 from the jack 5, thereby restoring all of the trunk circuit apparatus to normal condition.

While the called station is being signaled, the condenser 18 thereat becomes charged and, upon the release of the ringing key 7, a discharge may take place through the winding of supervisory relay 8, causing the momentary operation of such relay. Although a corresponding momentary operation of relay 10 is produced thereby, the ringing signal lamp 11 is not completely extinguished, due to the fact that the slow release relay 12 controls the locking circuit of relay 10 in such a way that relay 10 is not locked in its operated position until relay 12 has fully released. Thus no false signal is produced by the discharge of the capacitance of the line circuit upon the release of the ringing key 7 prior to the answer of the called station.

What is claimed is:

1. In a telephone exchange system, a line circuit, a station thereon, a trunk circuit for connection therewith, a signal control relay, a supervisory relay operating upon the answer of the station in response to a call originated by the trunk circuit to operate the signal control relay, means for locking the signal control relay upon the operation thereof, a signaling device operable upon the locking of the signal control relay, and means associated therewith to prevent the locking of the signal control relay upon the momentary operation thereof.

2. In a telephone exchange system, a line circuit, a station thereon, a trunk circuit for connection therewith, a signal control relay, a signaling device controlled thereby, a supervisory relay operating upon the answer of the station in response to a call when the trunk circuit is connected with the line circuit, said supervisory relay operating the signal control relay to cause a signal to be given by the signaling device, means for locking the signal control relay upon the operation thereof, and means associated with the signaling device for controlling the locking of the control relay to prevent the signal being given by the signaling device upon an incidental operation of the supervisory relay.

3. In a telephone exchange system, a line circuit having capacitance, a station thereon, a trunk circuit for connection therewith, a

- signal control relay responsive either to the answer of the called station or to the discharge of the capacitance, a locking winding for the signal control relay, a signaling device adapted to produce a signal upon the energization of the locking winding, and a slow release relay for preventing the energization of the locking winding upon the discharge of the capacitance.
- 5 10 4. In a telephone exchange system, a line circuit, a station thereon, a trunk circuit for connection therewith, a signal control relay

operating upon the response of the called station, a signaling device controlled thereby, a slow release relay associated with the 15 signaling device, and a locking circuit for the signal control relay completed upon the release of the slow release relay to cause a signal to be given by the signaling device.

In witness whereof, I hereunto subscribe 20 my name this 18th day of October, A. D., 1918.

DAWSON M. TAGGART.
